BOAT

Joseph A. Scruggs, Pensacola, Fla.

Application June 13, 1936, Serial No. 85,175

4 Claims. (Cl. 9—2)

The invention relates to a boat construction and more especially to a collapsible or knock-down boats.

The primary object of the invention is the provision of a boat of this character, wherein the sides and bottom of the same are formed in sections or panels, these being separably assembled so that when the boat is knocked down these sections or panels can be placed one upon the other as the latter lay flat thus making a very compact package.

Another object of the invention is the provision of a boat of this character, wherein the body of the latter may be built with or without gaskets or packings at the joints of the same, and by the employment of cables the side sections or panels of the body are hooped to hold the same in a longitudinal direction and also in contact with the bottom of said body, there being exerted an approximately equal inward pressure at all points along the sides of the boat, while dowel pins interlock with the sections or panels throughout the sides and bottom of said body.

A further object of the invention is the provision of a boat of this character, which is simple in construction, thoroughly reliable and efficient in its make-up, strong, durable, readily and easily knocked down and set up, and inexpensive to manufacture.

With these and other objects in view the invention consists in the features of construction, combination and arrangement of parts as will be hereinafter more fully described, illustrated in the accompanying drawings which disclose the preferred embodiment of the invention and pointed out in the claims hereunto appended.

In the accompanying drawings:

Figure 1 is a bottom plan view of the boat set up and constructed in accordance with the invention.

Figure 2 is a side elevation thereof.

Figure 3 is an enlarged vertical transverse sectional view.

Figure 4 is a fragmentary sectional view showing the manner of fastening the side with the bottom.

Figure 5 is a fragmentary perspective view of a modified form of fastener.

Figure 6 is a perspective view showing the manner of fastening the side sections or panels together.

Figure 7 is a fragmentary perspective view of the stern end of the boat.

Figure 8 is a fragmentary horizontal sectional view through the bow of the boat.

Figure 9 is a fragmentary perspective view of a modification showing the manner of fastening the side sections or panels together.

Figure 10 is a side view of another modification.

Figure 11 is a side view of a further modification.

Figure 12 is a sectional view on the line 12—12 of Figure 11.

Figure 13 is a view similar to Figure 12 showing the cam operating levers open.

Figure 14 is a sectional view on the line 14—14 of Figure 11.

Figure 15 is a section on the line 15—15.

Referring to the drawings in detail the boat 15 constituting the present invention comprises a body A composed of outwardly bulged sides B and a bottom C, respectively. The sides B are formed from a plurality of sections or panels 10 which in upright position make contact with each other 20 at their meeting edges 11 and in this position are separably fastened together by a swinging latching hook 12 and a staple-like keeper 13, respectively. Socketed in the meeting edges 11 of the sections or panels 10 are dowel pins 14 which 25 span the joints between the latter and interlock the same with each other.

The sections or panels 10 at the bow and stern ends of the body A have tongue and groove fittings 15 and 16, respectively with bow and stern 30 pieces 17 and 18, respectively.

The bottom C is formed from a plurality of sections or panels 19, which are arranged edge to edge for contact at their meeting edges 20 with each other, the joints of these being disposed 35 transversely of the bottom and staggered with respect to the joints of the side sections or panels 10.

The sections or panels 19 have beveled tongue and groove fitting 21 with the sections or panels 40 10 of the sides B, while the latter have an abutment overhang 22 with respect to the bottom C. Socketed in the meeting edges 20 of the sections or panels 19 are dowel pins 23 which span 45 the joints between the latter and separably interlock the same with each other.

The assembled bottom C is detachably secured to the sides B through the use of the latching hooks 24 and keepers 25, respectively.

Threaded through suitable transverse holes 26 50 in the bow piece 17 are longitudinally directed upper and lower side tying cables 27, these being trained rearwardly around the stern piece 18 and at their eye ends 28 have loose connection with turn-buckles 29 fastened by anchoring brackets 55

- 30 exteriorly to the said stern piece 18. These cables 27 when in tying positions rest in seating channels 31 formed externally in the side sections or panels 10.
- 5 Longitudinally of the bottom C outside of the same at its center is a tying cable 32 which is fixedly connected with the bow piece 17 and adjustably connected with the stern piece 18, respectively.
- 10 In Figure 5 of the drawings there is shown a slight modification of latching means, namely fixed interfitting hook and keeper 33 and 34, respectively, the hook being carried by the side section and the keeper by the bottom section 15 of the body of the boat.
- The side sections or panels 10 at their meeting edges 11 are cut-away at 35 on the inside to reduce the thickness of such edges 11 so that they will more readily compress through the 20 stress of the side cables 27 than the bottom sections or panels 19 to assure watertight seams at the joints between the said side sections or panels.
- The tensioning of the cables 27 and 32 is had by 25 the use of the turn-buckles in association therewith.
- In Figure 9 of the drawings there is shown a slight modification, wherein the stern end 36 of the boat has fixed thereto body plates 37 of 30 hooks 38, these being engaged by the eyes 39 of turn-buckle assemblies 40 which are linked to tying cables 41.
- In Figure 10 of the drawings there is shown another modification, wherein at the bow of the 35 boat is mounted a holding plate 42 having upper and lower rearwardly directed ears 43 and 44, respectively, these being linked at 45 to the tying cables 46.
- In Figures 11, 12, 13, 14 and 15 there is shown 40 a further modification, wherein at the bow 47 are fixed thereto spaced bearings 48 in which are journaled turning shafts 49 which are provided at opposite ends with eccentrics 50 having fitted in their outer faces eccentrically acting pivot 45 pins 51 on which are journaled eyes 52 of turn-buckle assemblies 53 linked at 54 with the tying cables 55. The shafts 49 have secured thereto actuating levers 56, these being shaped to conform to the shafts 49 for latching therewith at 57 when inwardly closed onto the same. The eccentrics 50 effect the tightening and slackening 50 of the tying cables at the sides of the boat.
- The cutaway section 35 is not absolutely necessary as the entire side panel may be reduced in 55 thickness to secure the same result. The tension in the cables not only tightens the joints between the side panels, but also tightens the joints between the side and bottom panels. This happens for the reason that the resistance to 60 compression in the side panels (due to the cutaway or thinner section or softer material) is less than the resistance of the bottom. This difference in resistance causes the sides to attempt to approach a straight line between the stern 65 and bow. This causes the side panels to fit snugly against the ends of the bottom panels forming a tight joint and with the correct shape at the joint 21 with the bottom in the boat without aid of the hooks and catches 24 and 25 or latch 70 33 and 34.

What is claimed is:

1. A knockdown boat of the kind described, comprising a sectional body including sides and a bottom, respectively, each formed of a plurality of separable sections, the sections being disposed edge to edge transversely of the body and bottom, a bow piece interfitting said body and bottom, the body and bottom being interlocked with said bow piece, a stern piece interfitting the body and bottom, overhangs formed on the sections of the 5 sides for the bottom sections and having the latter seated against the same for the interfitting thereof, and spaced upper and lower flexible elements arranged exteriorly of the body in longitudinal direction and adjustably coupled directly 10 to the bow and stern pieces for exerting equal inward pressure upon the sections of the body and pieces, respectively.
2. A knockdown boat of the kind described, comprising a sectional body including a bottom, 20 the sections being disposed edge to edge transversely of the body and bottom, a bow piece interfitting said body and bottom, a stern piece interfitting the body and bottom, flexible elements arranged exteriorly of the body in a longitudinal direction and adjustably coupled directly 25 to the bow and stern pieces for exerting equal inward pressure upon the sections of the body and pieces, respectively, means associated with said elements for increasing or decreasing the 30 pressure, turnable eccentrics connected with said means, and levers operating the eccentrics and latched at one end of the body.
3. A knockdown boat of the kind described, comprising a sectional body including a bottom, 35 the sections being disposed edge to edge transversely of the body and bottom, a bow piece interfitting said body and bottom, a stern piece interfitting the body and bottom, flexible elements arranged exteriorly of the body in a longitudinal 40 direction and adjustably coupled directly to the bow and stern pieces for exerting equal pressure inwardly upon the sections of the body and pieces, respectively, means associated with said elements for increasing or decreasing the pressure, turnable eccentrics connected with said means, levers operating the eccentrics and latched at one end of the body, and formations on the body for 45 seating the elements.
4. A knockdown boat of the kind described, 50 comprising a sectional body including a bottom, the sections being disposed edge to edge transversely of the body and bottom, a bow piece interfitting said body and bottom, a stern piece interfitting the body and bottom, flexible elements arranged exteriorly of the body and bottom in a longitudinal direction and adjustably coupled 55 directly to the bow and stern pieces for exerting equal pressure inwardly upon the sections of the body and pieces, respectively, means associated with said elements for increasing or decreasing the pressure, turnable eccentrics connected with said means, levers operating the eccentrics and latched at one end of the body, formations on 60 the body and bottom for seating the elements, and means interiorly on the body and engaged with the bottom for separable fastening the latter with the body.
